(57) **ABSTRACT**

The present invention provides an electronic cigarette and an atomizer assembly thereof. The atomizer assembly includes an air flowing pipe, a wick extending laterally through a sidewall of the air flowing pipe, and a heating member disposed within the air flowing pipe and engaging with the wick. The air flowing pipe defines opposite holes. The wick extends through the holes with opposite ends extending out of the air flowing pipe. The sidewall of the air flowing pipe further defines a cut communicating with the holes, to enable the wick being placed laterally into the holes. By virtue of the cut, two parts of the air flowing pipe divided by the cut are split off to form an open communicating with the closed holes, and the wick can be placed laterally into the holes via the open. Thus, the wick is easily installed without aligning and extending through the holes.

ELECTRONIC CIGARETTE AND ATOMIZER ASSEMBLY THEREOF

BACKGROUND

1. Technical Field

The present disclosure relates to an electronic atomizing device, and more particularly relates to an electronic cigarette.

2. Description of Related Art

The electronic cigarette is also known as a virtual cigarette or an electronic atomizer. As a substitute for cigarette, the electronic cigarette is usually used for smoking cessation. The appearance and taste of electronic cigarette are similar to those of the conventional cigarette, while it does not contain tar, suspended particles and other harmful ingredients as the conventional cigarette.

The related electronic cigarette includes a cylindrical housing, an atomizer assembly, a battery assembly, a liquid solution reservoir, a mouthpiece, and an end cover. The atomizer assembly, the battery assembly and the liquid solution reservoir are housed in the cylindrical housing. The mouthpiece and the end cover are respectively mounted to two opposite ends of the cylindrical housing. The related electronic cigarette functions as a substitute of tobacco in a certain extend. However, the atomizer assembly of the related electronic cigarette generally includes an air flowing pipe, a sleeve sleeves on the air flowing pipe, a solution guiding rope extending through the air flowing pipe via a hole defined therein, and a heating member fastened to the solution guiding rope. In assembly, the solution guiding rope is aligned with the hole and further extends therethrough, which is inconveniently and thus result in poorly inefficient.

Therefore, there is a perspective for improvement in the art.

SUMMARY

Embodiments of the present invention relate to an electronic cigarette and an atomizer assembly to overcome the above-mentioned disadvantage.

The atomizer assembly used for an electronic cigarette, includes an air flowing pipe, a wick extending laterally through a sidewall of the air flowing pipe, and a heating member disposed within the air flowing pipe and engaging with the wick. The sidewall of the air flowing pipe defines two opposite holes. The wick extends through the holes with two opposite ends thereof extending out of the air flowing pipe. The sidewall of the air flowing pipe further defines a cut. The cut communicates with the holes, thereby enabling the wick being placed into the holes by passing through the cut.

Wherein, the cut in some embodiments is arranged above the holes.

Wherein, the cut in some embodiments comprises a first section extending laterally and outwardly and a second section connected to the first section, the second section extends to and communicates with the holes.

Wherein, the heating member in some embodiments is a wire and coils around a section of the wick disposed within the air flowing pipe.

Wherein, the atomizer assembly further includes a positioning sleeve; the positioning sleeve sleeves on a portion of the air flowing pipe where the cut is defined.

Wherein, in some embodiments, the inner diameter of the positioning sleeve is substantially equal to the outer diameter of the air flowing pipe.

The electronic cigarette includes a cigarette, a mounting base, a reservoir, a power supply assembly, a mouthpiece defining a center through hole, an end cover, and an atomizer assembly. The atomizer assembly includes an air flowing pipe, a wick extending laterally through a sidewall of the air flowing pipe, and a heating member disposed within the air flowing pipe and engaging with the wick. The sidewall of the air flowing pipe defines two opposite holes. The wick extends through the holes with two opposite ends thereof extending out of the air flowing pipe. The sidewall of the air flowing pipe further defines a cut. The cut communicates with the holes, thereby enabling the wick being placed into the holes by passing through the cut. The mouthpiece and the end cover cover two opposite ends of the housing respectively. The mounting base, the atomizer assembly, the reservoir, and the power supply assembly are disposed within the housing. The mounting base is arranged within the middle of the housing. The atomizer assembly is mounted to the mounting base and is arranged between the mouthpiece and the mounting base. The reservoir is disposed at the peripheral of the atomizer assembly. The power supply assembly is arranged between the mounting base and the end cover and is electrically connected to the atomizer assembly.

Wherein, the mounting base in some embodiments includes an elastic body engaging with an inner sidewall of the housing and a rigid support for supporting the atomizer assembly, the elastic body defines a first centre hole, and the rigid support is plugged into the first center hole.

Wherein, the rigid support in some embodiments includes a first inserting portion, a main portion, and a second inserting portion, and is plugged into the atomizer assembly and the elastic body respectively, the rigid support defines a second center hole; the second center hole extends through the first inserting portion, the main portion, and the second inserting portion in sequence, to guide air below the mounting base to enter into the atomizer assembly; the inlet of the air flowing pipe of the atomizer assembly sleeves on the first inserting portion, and the outlet of the air flowing pipe faces the center through hole defined in the end cover.

Wherein, the electronic cigarette in some embodiments further includes a supporting pipe, the supporting pipe is plugged into the outlet of the air flowing pipe, and is spaced apart from the end cover.

Wherein, the cut in some embodiments includes a first section extending laterally and outwardly and a second section connected to the first section, the second section extends to and communicates with the holes.

Wherein, the heating member in some embodiments is a wire and coils around a section of the wick disposed within the air flowing pipe.

Wherein, the atomizer assembly in some embodiments further includes a positioning sleeve; the positioning sleeve sleeves on a portion of the air flowing pipe where the cut is defined.

Wherein, in some embodiments, the inner diameter of the positioning sleeve is substantially equal to the outer diameter of the air flowing pipe.

In the present invention, by virtue of the cut defined in the air flowing pipe and communicating with the holes, two parts of the air flowing pipe divided by the cut are split off to form an open communicating with the holes, and the wick can be placed laterally into the holes via the open. Thus, the wick is easily installed without aligning and extending through the holes.

BRIEF DESCRIPTION OF THE DRAWINGS

Many aspects of the embodiments can be better understood with reference to the following drawings. The com-

ponents in the drawings are not necessarily drawn to scale, the emphasis instead being placed upon clearly illustrating the principles of the embodiments. Moreover, in the drawings, like reference numerals designate corresponding parts throughout the several views.

FIG. 1 is a perspective view of an electronic cigarette in an embodiment.

FIG. 2 is a top view of the electronic cigarette shown in FIG. 1.

FIG. 3 is a cross-sectional view taken along line A-A of FIG. 2; the electronic cigarette includes a mouthpiece, an end cover, an atomizer assembly, a reservoir, a mounting base, and a light emitting unit.

FIG. 4 is a cross-sectional view taken along line B-B of FIG. 2.

FIG. 5 is an enlarged cross-sectional view of the mouthpiece of the electronic cigarette shown in FIG. 3.

FIG. 6 is a perspective view of the mouthpiece of the electronic cigarette shown in FIG. 3.

FIG. 7 is a perspective view of the end cover of the electronic cigarette shown in FIG. 3.

FIG. 8 is similar to FIG. 7, but viewed from another aspect.

FIG. 9 is a perspective view of the mounting base of the electronic cigarette shown in FIG. 3.

FIG. 10 is an exploded view of the mounting base of FIG. 9; the mounting base includes an elastic body and a rigid support.

FIG. 11 is a perspective view of the elastic body of the mounting base in FIG. 9 in another aspect.

FIG. 12 is an enlarged cross-sectional view of the elastic body in FIG. 11.

FIG. 13 is an enlarged view of the rigid support of the mounting base in FIG. 3.

FIG. 14 is an enlarged view of the rigid support of the mounting base in FIG. 4.

FIG. 15 is a bottom view of the rigid support in FIG. 10.

FIG. 16 is an enlarged cross-sectional view of the mounting base in FIG. 4.

FIG. 17 is an enlarged cross-sectional view of the mounting base in FIG. 3.

FIG. 18 is an enlarged cross-sectional view of the atomizer assembly in FIG. 3.

FIG. 19 is a perspective view of the atomizer assembly in FIG. 3.

FIG. 20 is an exploded view of the atomizer assembly in FIG. 19.

FIG. 21 is a perspective view of the air flowing pipe of the atomizer assembly, showing the air flowing pipe being split off along a cut.

FIG. 22 is a perspective view of the reservoir of FIG. 3.

FIG. 23 is a perspective view of the end cover in FIG. 3 after the light emitting unit is assembled.

FIG. 24 is a perspective view of an atomizer assembly in a second embodiment.

FIG. 25 is a perspective view of an atomizer assembly in a third embodiment.

FIG. 26 is a perspective view of an air flowing pipe in a second embodiment.

FIG. 27 is a perspective view of an air flowing pipe in a third embodiment.

FIG. 28 is a perspective view of an air flowing pipe in another embodiment.

FIG. 29 is a perspective view of a tubular tool in the embodiment.

ough understanding of and enabling description for these embodiments. One skilled in the art will understand that the disclosure may be practiced without such details. In other instances, well-known structures and functions have not been shown or described in detail to avoid unnecessarily obscuring the description of the embodiments.

Unless the context clearly requires otherwise, throughout the description and the claims, the words "comprise," "comprising," and the like are to be construed in an inclusive sense as opposed to an exclusive or exhaustive sense; that is to say, in the sense of "including, but not limited to." Words using the singular or plural number also include the plural or singular number respectively. Additionally, the words "herein," "above," "below" and words of similar import, when used in this application, shall refer to this application as a whole and not to any particular parts of this application. When the claims use the word "or" in reference to a list of two or more items, that word covers all of the following interpretations of the word: any of the items in the list, all of the items in the list and any combination of the items in the list.

FIGS. 1-4, illustrate an electronic cigarette 1 in an embodiment. The electronic cigarette 1 includes a cylindrical housing 10, a mouthpiece 20, an end cover 30, a mounting base 40, an atomizer assembly 50, a reservoir 60 for storing liquid solution, a power supply assembly 70, an air switch 80, and a light emitting unit 90.

The mouthpiece 20 and the end cover 30 are mounted to two opposite ends of the housing 10 respectively. The mounting base 40, the atomizer assembly 50, the reservoir 60 and the power supply assembly 70 are disposed within the housing 10. The mounting base 40 is arranged in the middle of the housing 10. The atomizer assembly 50 is mounted to the mounting base 40 and is located between the mounting base 40 and the mouthpiece 20. The reservoir 60 is mounted to the mounting base 40 and wraps the atomizer assembly 50. The power supply assembly 70 is arranged between the mounting base 40 and the end cover 30. The power supply assembly 70 is electrically connected to the atomizer assembly 50. The air switch 80 is disposed within the end cover 30. The light emitting unit 90 is mounted on the air switch 80. The air switch 80 and the light emitting unit 90 are electrically connected to the power supply assembly 70.

The housing 10 in some embodiments is substantially cylindrical. The housing 10 is made of resilient material, such as elastic plastic, whereby enabling deformation when extruded radially by the user, to simulate a touch sensation of a cigarette. It is noteworthy that the housing 10 can be rectangular, oval, and so on. The housing 10 can also be made of rigid material, such as steel.

Referring to FIGS. 5 and 6, the mouthpiece 20 is made of resilient material, such as silicone. The mouthpiece 20 includes a main body 21, a ring 23, a guiding boss 25 and a flange 27. The main body 21 is substantially cylindrical. The diameter of the main body 21 is slightly greater than the diameter of a hole defined in an end of the housing 10 for receiving the mouthpiece 20, whereby enabling the mouthpiece 20 to tightly engage with the housing 10 by an interference fit, for avoiding leakage of the liquid solution via the clearance between the housing 10 and the mouthpiece 20.

The main body 21 in the embodiment includes an inner end surface 211 and an outer end surface 212. The inner end surface 211 is opposite to the outer end surface 212. The main body 21 defines a center through hole 210. The center through hole 210 extends from the inner end surface 211 to

DETAILED DESCRIPTION

Illustrative embodiments of the disclosure are below. The following explanation provides specific details for a thor-

the outer end surface 212. The center through hole 210 allows atomizer generated by the atomizer assembly 50 flowing out of the housing 10. The ring 23 protrudes from the inner end surface 211 and surrounds the center through hole 210, to elongate the distance of the liquid solution flows from the edge of the inner end surface 211 to the center through hole 210, whereby reducing probability of leakage of the liquid solution via the center through hole 210.

In some embodiments, the outer surface of the main body 21 of the mouthpiece 20 recesses radially and inwardly to form a ring groove 214, the ring groove 214 is to accommodate liquid solution which leakages from the clearance between the inner surface of the housing 10 and the side wall of the main body 21, whereby enhancing the engagement tightness of the mouthpiece 20 and the housing 10. Furthermore, because of the existence of liquid surface tension, the configured ring groove 214 greatly improves the resistance of fluid extends toward the corresponding end of the housing 10, which can significantly reduce the probability of leakage of liquid solution. It should be noteworthy that the number of the ring groove 214 is not limited to one, two or more ring grooves can be defined and are spaced apart.

The guiding boss 25 extends from the rim of the inner end surface 211 of the main body 21 in a direction adjacent to the atomizer assembly 50. The distal end of the guiding boss 25 defines a substantially tapered guiding surface. Because of the guiding boss 25, the mouthpiece 20 is mounted conveniently, at the same time, the distance of the solution flows from the sidewall of the housing 10 to the center through hole 210, whereby enhancing difficulty of leakage of the solution via the center through hole 210.

In some embodiments, the flange 27 extends radially and outwardly from the side wall of the main body 21 and is coplanar with the outer end surface 212. Referring to FIGS. 3 and 4, the outer diameter of the flange 27 is substantially equal to that of the end of the housing 10 where the mouthpiece 20 is mounted. As a result, when the mouthpiece 20 is plugged into the housing 10, the flange 27 abuts tightly against the inner surface of the housing 10. On one hand, the flange 27 prevents the mouthpiece 20 from being plugged excessively into the housing 10, on the other hand, the flange 27 allows the mouthpiece 20 to be easily pulled out.

Referring to FIGS. 7 and 8, in some embodiments, the end cover 30 is integrally formed by hard plastic injection molding. The end cover 30 includes a bottom wall 31 and a cylindrical sidewall 33 extending from the bottom wall 31. The bottom wall 31 covers the corresponding end of the housing 10, the sidewall 33 is tightly plugged into the housing 10, whereby the end cover 30 is mounted to the housing 10.

The bottom wall 31 defines an aperture 313 and an air inlet 314. The aperture 313 extends through the bottom wall 31, to communicate the inner space of the end cover 30 with the outside. The air inlet 314 is defined on the outer surface of the bottom wall 31, whereby allowing air to enter into the housing 10. In some embodiments, the bottom wall 31 includes an annular enclosure 311 and a cover plate 312 coupled to the annular enclosure 311. The aperture 313 and the air inlet 314 are defined on the annular enclosure 311. The outer diameter of the annular enclosure 311 is substantially equal to that of the end (hereinafter, first end) of the housing 10 where the end cover 30 is mounted. When the end cover 30 is plugged into the housing 10, the annular enclosure 311 tightly abuts against the inner surface of the housing 10. The cover plate 312 includes at least a transparent portion, whereby enabling light emitted by the light emitting unit 90 transmitting therethrough to simulate fire-

work effect of burning cigarette. The transparent portion can be a top area of the cover plate 312, and can also be the whole of the cover plate 312. The cover plate 312 in the embodiment is substantially hemispherical, to simulate fire-work effect of burning cigarette more real and beautiful.

In some embodiments, the sidewall 33 defines a cutout 334. The cutout 334 extends through the inner wall and the outer wall of the sidewall 33. Referring to FIG. 23, wires 81 pass through the cutout 334 to electrically connect the air switch 80 to the power supply assembly 70. The outer wall of the sidewall 33 further defines an outer guiding groove 335. The outer guiding groove 335 extends from an end of the sidewall 33 away from the cover plate 312 to the bottom wall 31. The outer guiding groove 335 communicates with the air inlet 314, whereby enabling air passing through the air inlet 314 and the outer guiding groove 335 in sequence and further entering into the housing 10 to take smoke generated by the atomizer assembly 50 away.

The sidewall 33 in some embodiments further defines a step 330. The step 330 is arranged at the inner surface of the sidewall 33. The air switch 80 is accommodated within the end cover 30 and is mounted to the step 330. The light emitting unit 90 is mounted to a side of the air switch 80 facing the bottom wall 31. An internal space between the air switch 80 and the bottom wall 31 communicates with the outside with the aperture 313, to keep the internal and external pressure in a balance. Air which entries into the end cover 30 via the aperture 313, changes the pressure below the step 330, and the air switch 80 is actuated by the variation of air pressure.

Referring to FIGS. 7 and 8 again, the sidewall 33 in some embodiments is substantially step-cylindrical. The sidewall 33 includes a first column 331, a second column 333, and a transmission portion 332 coupling the first column 331 with the second column 333. The diameter of the first column 331 is greater than that of the second column 333. The first column 331 extends from the annular enclosure 311 of the bottom wall 31. The outer diameter of the first column 331 is slightly greater than the inner diameter of the first end of the housing 10, but is less than the outer diameter of the first end, whereby enabling the end cover 30 engaging with the housing 10 by an interference fit. The outer diameter of the second column 333 is less than the inner diameter of the first end. The second column 333 and the transmission portion 332 cooperatively guide the installation of the side wall 33.

The step 330 in some embodiments is arranged at the junction of the transmission portion 332 and the second column 333, to enhance the strength for supporting the air switch 80, and to protect the installing of the end cover 30 from being hindered. The cutout 334 extends from an end of the first column 331 away from the bottom wall 31 to the bottom wall 31, whereby enabling wires electrically connected to the air switch 80 to pass therethrough. The outer guiding groove 335 extends from an end of the first column 331 away from the bottom wall 31 to the bottom wall 31, and communicates with the air inlet 314, to allow air entering into the housing 10 by passing through the air inlet 314, the outer guiding groove 335 in sequence. In some embodiments, the inner surface of the sidewall 33 further defines an inner guiding groove 336. The inner guiding groove 336 extends from an end of the first column 331 away from the bottom wall 31 to the bottom wall 31, and communicates with the aperture 313, whereby enabling air to entry into the housing 10 by passing through the aperture 313 and the inner guiding groove 336.

Referring to FIGS. 9 and 10, the mounting base 40 in some embodiments includes an elastic body 41 and a rigid

support 43. The elastic body 41 engages with the inner surface of the housing 10. The rigid support 43 is used for mounting the atomizer assembly 50. The center of the elastic body 41 defines a first center hole 410, for allowing the rigid support 43 to be plugged thereinto. Because the mounting base 40 is composed of the elastic body 41 and the rigid support 43, the housing 10 is tight by the elastic body 41 when the mounting base 40 is mounted to the housing 10, and the atomizer assembly 50 is better supported by the rigid support 43.

The elastic body 41 in some embodiments is cylindrical, and is made of elastic material, such as rubber. The elastic body 41 includes a top end surface 411, a bottom end surface 412 opposite to the top end surface 411, and a sidewall surface 413 connecting the top end surface 411 with the bottom end surface 413. The first center hole 410 extends from the top end surface 411 to the bottom end surface 412. The inner surface of the first center hole 410 is provided with at least two annular protrusions 4101 (see FIG. 12). The annular protrusions 4101 are spaced apart. When the second embedding portion 433 of the rigid support 43 is inserted into the first centre hole 410, the annular protrusions 4101 tightly abut against the second embedding portion 433 to enhance tightness between the second embedding portion 433 and the inner surface of the first centre hole 410. The center of the top end surface 411 recesses to define a receiving portion 4110. The receiving portion 4110 is substantially cylindrical, and is coaxial to the elastic body 41.

Referring also to FIG. 11, the bottom end surface 412 of the elastic body 41 recesses to define a plurality of guiding slots 4120. The guiding slots 4120 surround the first center hole 410 and are arranged radially. Each guiding slot 4120 extends from the sidewall surface 413 to the first center hole 410, whereby enabling air to enter into the first centre hole 410.

In some embodiments, the bottom end surface 412 further recesses to define a number of accommodating slots 4122 for accommodating glue, namely, the accommodating slots 4122 functions as glue-dispensing slot. The number of the accommodating slots 4122 is substantially equal to that of the guiding slots 4120. The accommodating slots 4122 correspond to the guiding slots 4120. Each accommodating slot 4122 intersects with the corresponding guiding slot 4120. The axis of the elastic body 41 is equidistant from the accommodating slots 4122. The depth of each accommodating slot 4122 is preferably equal to the depth of the corresponding guiding slot 4120. Each accommodating slot 4122 in some embodiments is substantially waist-shaped, and perpendicularly intersects with the corresponding guiding slot 4120. The number of the accommodating slot 4122 is preferably more than two, to receive cathode and anode wires 531 of the atomizer assembly 50 (see FIG. 17).

Referring to FIG. 11 again, the bottom end surface 412 further recesses to define an annular step 4123. The annular step 4123 surrounds the first center hole 410. The annular step 4123 engages with the second inserting portion 433 of the rigid support 43 (see FIG. 13), to lock the rigid support 43 to the elastic body 41. Preferably, the annular step 4123 is coplanar with the bottom of the guiding slots 4120.

Referring also to FIG. 12, the elastic body 41 in some embodiments further defines a number of extending holes 414. Each extending hole 414 extends from the top end surface 411 toward the bottom end surface 412, and a stopping block 415 is formed between the bottom of the extending hole 414 and the bottom end surface 412. The number of the extending holes 414 is substantially equal to the number of the accommodating slots 4122, and the

extending holes 414 correspond to the accommodating slots 4122 respectively. Each extending hole 414 extends from the top end surface 411 in a direction adjacent to the corresponding accommodating slot 4122. Preferably, the extending hole 414 is a blind hole, and extends from the bottom of the receiving portion 4110 in a direction toward the bottom of the corresponding accommodating slot 4122, a stopping block 415 is formed between the bottom of the extending hole 414 and the bottom of the corresponding accommodating slot 4122.

Referring to FIG. 17, wires 531 of the atomizer assembly 50 can pierce through the stopping block 415, and are further electrically connected to the power supply assembly 70. The wires 531 pierce the stopping block 415 to form piercing hole 416. The accommodating slot 4122 corresponding to the stopping block 415 which pierced by the wires 531 is dispensed with glue, to secure the wires 531. Because the elastic body 41 is made of elastic material, such as silicone, when the wires 531 pierce through the stopping block 415, the pierced hole 416 is deformable. When the wires 531 are received in the piercing hole 416, the wires 531 are tightly fastened by the sidewall of the piercing hole 416, to archive sealing effect. Furthermore, the stopping block 415 prevents the glue from flowing into the extending hole 414, thus, the wires 531 can be secured with less glue, and the liquid solution is also protected from being polluted by the glue.

In some embodiments, the number of the extending holes 414 is preferably two or more than two, to allow the cathode and anode wires 531 of the atomizer assembly 50 to pierce respectively. When the rigid support 43 has positioning posts 435, the number of the extending hole 414 increases correspondingly. For example, the number of the extending holes 414 illustrated in the FIGS is four, at this time, because some of the extending holes 414 are used for allowing the wires 531 piercing through the stopping block 415, and the other extending holes 414 are used for allowing the positioning posts 435 to be inserted thereinto, the configuration of the extending holes 414 being arranged surrounding the first center hole 410 is important, such that any extending holes 414 can be used for allowing the wires 531 and the positioning posts 435 to be inserted thereinto. In other words, it is not need to assign the extending holes 414 to be used for allowing the wires 531 and the positioning posts 435 in advance, thereby enabling the electronic cigarette 1 being installed conveniently.

Referring to FIGS. 12 and 17, each extending hole 414 is preferably cylindrical, and includes a first portion 4141, a second portion 4143, and a connecting portion 4142 for communicating the first portion 4141 with the second portion 4143. The diameter of the first portion 4141 is greater than that of the second portion 4143. The stopping block 415 is arranged between the second portion 4143 and the corresponding accommodating slot 4122. The diameter of the first portion 4141 is not greater than the diameter of the positioning post 435 of the rigid support 43. The depth of the first portion 4141 is not less than the length of a portion of the positioning post 435 which being inserted into the extending hole 414. The diameter of the second portion 4143 is less than that of the first portion 4141, to reduce the size of the stopping block 415, and thus the elasticity of the stopping block 415 is enhanced. As a result, when the wires 531 pierce through the stopping block 415, a greater elastic force is generated by the stopping block 415 to fasten the wires 531 tightly, to achieve a better sealing effect. Preferably, the cross section of the connecting portion 4142 is substantially frustum, to guide the wires 531 to pierce through the stopping block 415.

Referring to FIGS. 10-12, in some embodiments, a plurality of annular flange 4130 protrudes radially and outwardly from the sidewall 413 of the elastic body 41. Each annular flange 4130 extends along the contour of the sidewall 413. Two adjacent annular flanges 4130 are spaced apart from each other, thereby the sidewall 413 is substantially wavy. The maximum outer diameter of the annular flange 4130 is greater than the inner diameter of the housing 10, such that the annular flange 4130 tightly engages with the housing 10 when the elastic body 41 plugs into the housing 10, thereby achieving a good sealing effect, to prevent the liquid solution from flowing from the top end of the elastic body 41 to the bottom end of the elastic body 41 along the sidewall 413.

Referring to FIG. 10 and FIGS. 13-15, the rigid support 43 in some embodiments is integrally formed by plastic injection molding. The rigid support 43 includes a first inserting portion 431, a main portion 432, a second inserting portion 433, and a pair of positioning posts 435. The first inserting portion 431 is inserted into the atomizer assembly 50, and the second inserting portion 433 is inserted into the first centre hole 410 from the top end surface 411 of the elastic body 40. The rigid support 43 further defines a second center hole 434. The second center hole 434 is used to guide air below the mounting base 40 to enter into the atomizer assembly 50. The positioning posts 435 are inserted into the extending holes 414, to prevent the rigid support 43 from rotating relative to the elastic body 41.

The first inserting portion 431 and the second inserting portion 433 are coupled to two opposite ends of the main portion 432 respectively. The second center hole 434 extends through the first inserting portion 431, the main portion 432 and the second inserting portion 433 in sequence. The positioning posts 435 protrudes from the main portion 432. The positioning posts 435 and the second inserting portion 433 are arranged at the same end of the main portion 432, and the positioning posts 435 are respectively arranged at two opposite sides of the second inserting portion 433.

Referring to FIGS. 10 and 13 again, the main portion 432 in some embodiments includes a first end surface 4321, a second end surface 4322 opposite to the first end surface 4321. The center of the first end surface 4321 recesses to define an accommodating portion 4323. The first inserting portion 431 protrudes from the bottom of the accommodating portion 4323. The second inserting portion 433 protrudes from the centre of the second end surface 4322. The accommodating portion 4323 in some embodiments is substantially cylindrical, and is coaxial with the second center hole 434. The accommodating portion 4323 is used to receive the reservoir 60. The positioning posts 435 are coupled to the second end surface 4322.

Referring to FIGS. 14 and 15, in some embodiments, the main portion 432 of the rigid support 43 defines a pair of receiving holes 436. The receiving holes 436 are arranged at two opposite sides of the second inserting portion 433, to allow cathode and anode wires 531 of the atomizer assembly 50 (see FIG. 17) to pass through respectively. The pair of the receiving holes 436 and the pair of positioning posts 435 are evenly spaced apart and surround the second center hole 434, and the second center hole 434 are equidistant from the receiving holes 436 and the positioning posts 435 (see FIG. 15). The receiving holes 436 and the positioning posts 435 correspond to the extending holes 414 respectively.

Referring to FIGS. 13 and 14, the main portion 432 in some embodiments is substantially step-cylindrical, and includes a first segment 4324, a second segment 4325, and

a third segment 4326. The first segment 4324, the second segment 4325 and the third segment 4326 are arranged coaxially between the first end surface 4321 and the second end surface 4322. The first segment 4324 and the third segment 4326 are arranged at two opposite ends of the second segment 4325. The diameter of the second segment is substantially equal to the inner diameter of the housing 10. The diameter of the second segment 4325 is greater than the diameter of the first segment 4324, to form an annular step 4327 (see FIG. 10). When the mounting base 40 is mounted to the housing 10, the tubular tool 2 abuts against the annular step 4327 to install the mounting base 40 to the housing 10 easily.

In detail, the tubular tool 2 is illustrated in FIG. 29. The diameter of the tubular tool 2 is greater than the diameter of the first segment 4324, but is slightly less than the inner diameter of the housing 10. When the mounting base 40 is to be installed to the housing 10, the tubular tool 2 is firstly inserted into the first segment 4324, then, the mounting base 40 is aligned with the housing 10, and is further plugged into the housing 10 by the tubular tool 2. At this time, because the tubular tool 2 abuts against the annular step 4327, a pressure is evenly exerted on the mounting base 40 by the tubular tool 2, to prevent the mounting base 40 from slanting or being stuck, whereby enabling the mounting base 40 being installed accurately.

The diameter of the third segment 4326 of the main portion 432 is less than that of the second segment 4325, and is substantially equal to the diameter of the receiving portion 4110 of the elastic body 41. The length of the third segment 4326 in axis direction is substantially equal to the depth of the receiving portion 4110, to enable the third segment 4326 to be fitly inserted into the receiving portion 4110 (see FIG. 16). When the third segment 4326 has been inserted into the receiving portion 4110, the second segment 4325 tightly abuts against the top end surface 411 of the elastic body 41.

Referring to FIGS. 13 and 15, a hook-shaped limiting member 4330 is arranged adjacent to the distal end of the second inserting portion 433. The limiting member 4330 is arranged along the contour of the second inserting portion 433. The diameter of the limiting member 4330 is greater than the diameter of the first center hole 410 of the elastic body 41.

Referring to FIG. 16, the distance between the limiting member 4330 and the bottom end surface 4322 of the main portion 432 is substantially equal to the distance between the bottom of the receiving portion 4110 and the annular step 4327, such that when the second inserting portion 433 is plugged into the first centre hole 410, the limiting member 4330 tightly hooks the annular step 4327, to prevent the second inserting portion 433 from loosing or detaching from the first center hole 410.

Referring also to FIG. 14, the front end of the limiting portion 4330 in some embodiments includes a guiding portion 4332. The guiding portion 4332 is substantially tapered, for guiding the limiting portion 4330 to pass through the first center hole 410. Referring also to FIG. 3, the length of the limiting portion is substantially equal to distance between the bottom end surface 412 of the elastic body 41 and the annular step 4327, thus, when the second inserting portion 433 is plugged into the first center hole 410, the distal end of the second inserting portion 433 extends out of the bottom end surface 412 of the elastic body 41. The distal end of the second inserting portion 433 prevents the power supply assembly 70 from abutting against the bottom end surface of the elastic body 41,

thereby providing space for allowing wires 531 to pass through, and preventing air duct from being blocked.

Referring also to FIGS. 10, 14 and 15, the middle of the sidewall of the second inserting portion 433 recesses to define a groove 4334. The groove 4334 extends from the end surface of the second inserting portion 433 to the top end surface of the limiting portion 4330 in a direction parallel to the axis of the second inserting portion 433, and extends laterally and upwardly through the second inserting portion 433 and the limiting portion 4330, to communicate with the guiding slot 4120 of the elastic body 41 (see FIG. 16). Thus, air can enter into the atomizer assembly 50 by passing through the guiding slot 4120, the groove 4334, and the second center hole 434 in sequence.

Referring to FIG. 15, the projection of the groove 4334 on the second end surface 4322 is aligned with the pair of the positioning posts 435. Thus, when the electronic cigarette 1 has been installed (see FIG. 16), the groove 4334 faces the guiding slot 412 with no wires 531, to prevent air from being blocked by the wires 531 and/or solidified glue for fixing the wires 531. Referring to FIG. 17, when the electronic cigarette 1 has been installed, the guiding slot 4120 which wires 531 pass through is blocked by the second engaging portion 433, thereby preventing the wires 531 and/or glue from being adversely affected by the flowing air.

Referring to FIGS. 18 and 19, the atomizer assembly 50 in some embodiments includes an air flowing pipe 51, a wick 52, a heating member 53, a positioning sleeve 54, and a supporting pipe 55. An end (inlet) of the air flowing pipe 51 sleeves the first inserting portion 431 of the rigid support 43 (see FIGS. 3 and 4), the other end (outlet) of the air flowing pipe 51 faces the center through hole 210. The wick 52 is made of fiber glass, and traverses the sidewall of the center through hole 210 with two opposite ends extending out of the air flowing pipe 51, to suck solution in the reservoir 60 into the air flowing pipe 51 by capillarity. The heating member 53 is received in the air flowing pipe 51 and engages with the wick 52. In the embodiment, the heating member 53 mainly engages with a portion of the wick 52 disposed in the air flowing pipe 51, and atomizes the solution sucked in the wick 52 by heating. The positioning sleeve 54 sleeves on the air flowing pipe 51 and is coaxial with the air flowing pipe 51, to reinforce a particular portion of the air flowing pipe 51. The supporting pipe 55 sleeves on the outlet of the air flowing pipe 51 to protect the air flowing pipe 51 from being deformed when pressed, thereby preventing the air flowing pipe 51 from blocking smoke flow therein. The supporting pipe 55 further prevents the reservoir 60 from being excessively deformed when an external force radially exert on the electronic cigarette 1, thus, leakage of a large amount of solution from the reservoir 60 is avoided. Furthermore, the supporting pipe 55 is spaced apart from the ring 23, to prevent solution on the supporting pipe 55 from transferring to the ring 23. Referring to FIG. 20, the air flowing pipe 51 in some embodiments is substantially a long cylindraceous, and is made of fibre. The diameter of the inlet of the air flowing pipe 51 is less than the diameter of the first engaging portion 431 of the rigid support 43, thereby enabling the air flowing pipe 51 being plugged into the first inserting portion 431 by an interference fit. The sidewall of the air flowing pipe 51 defines two opposite holes 510. The diameter of the holes 510 is suitable for receiving the wick 52. Two opposite ends of the wick 52 extend out of the air flowing pipe 51. For conveniently installing the wick 52, a cut 512 is defined in the sidewall of the air flowing pipe 51. The cut 512 communicates with the holes 510, to allow the wick 52 being placed laterally into

the holes 510 via the cut 512, thereby enabling the wick 52 being installed easily. In some embodiments, the cut 512 is arranged above the holes 510.

Referring to FIG. 21, the cut 512 allows two portions of the air flowing pipe 51 divided by the cut 512 to be split to angle with each other, thus, an open is defined and communicates with the holes 510. The open allows the wick 52 to be placed laterally into the holes 510 without aligning and extending through the holes 510. The wick 52 in some embodiments includes a first section 5121 and a second section 5123 connected to the first section 5121. The first section 5121 extends laterally and outwardly. The second section 5123 extends to and communicates with the holes 510. Preferably, the angle between the first section 5121 and the second section 5123 is an obtuse angle. It is noteworthy that the angle between the first section 5121 and the second section 5123 can be a right angle.

Because of the cut 512 defined in the air flowing pipe 51, the strength of the air flowing pipe decreases in some certain. When pressed by an external force, such as the pressure of the reservoir 60, the probability of a position of the air flowing pipe 51 corresponding to the cut 512 being collapsed increases, which may result in a problem. To overcome this problem, a positioning sleeve 54 sleeves on the air flowing pipe 54 and corresponds to the cut 512, thus, the external force exerted on the air flowing pipe 51 disperses to other portions of the air flowing pipe 51, to reduce the external force focusing on the position of the air flowing pipe 51 corresponding to the cut 512. The positioning sleeve 54 and the air flowing pipe 51 are made of the same material. The inner diameter of the positioning sleeve 54 is substantially equal to the outer diameter of the air flowing pipe 51. The length of the positioning sleeve 54 is greater than the maximum length of the cut 512 extending along the longitude of the air flowing pipe 51. As a result, the positioning sleeve 54 is enabled to tightly sleeve on the air flowing pipe 51 to cover the cut 512, thereby enhancing the resistance of the air flowing pipe 51.

Referring also to FIG. 21, the heating member 53 in some embodiments is wire. The heating member 53 coils around the portion of the wick 52 disposed in the air flowing pipe 51, to atomize solution sucked in the wick 52 by heating. Referring also to FIGS. 3 and 17, two opposite ends of the heating member 53 are electrically connected to two wires 531 respectively. The wires 531 extend out of the air flowing pipe 51 by passing through the holes 510, and then extend through the receiving hole 436 of the rigid support 43, the extending hole 413 of the elastic body 41 in sequence, and further penetrate through the stopping block 415 to be electrically connected to the power supply assembly 70.

The supporting pipe 55 in some embodiments is made of hard plastic. The supporting pipe 55 includes a first pipe 552, a transmission pipe 553 connected to the first pipe 552, a second pipe 554 connected to an end of the transmission pipe 553 opposite to the first pipe 552, and a resisting portion 555. The outer diameter of the first pipe 552 is slightly greater than the inner diameter of the air flowing pipe 51, to enable the first pipe 552 being plugged into the air flowing pipe 51 by an interference fit. The outer diameter of the second pipe 554 is slightly greater than the outer diameter of the first pipe 552. The cross section of the transmission pipe 553 is substantially tapered. An end of the transmission pipe 553 with bigger diameter is connected to the second pipe 554, the other end of the transmission pipe 553 is connected to the first pipe 552, thereby the first pipe 552 is connected to the second pipe 554 via the transmission pipe 553. Because the first pipe 552 and the second pipe 554 are

13

interference fit with the air flowing pipe 51 respectively, the supporting pipe 55 are tightly secured to the air flowing pipe 51. The outer diameter of the resisting portion 555 is greater than the outer diameter of the air flowing pipe 51, and the resisting portion 555 abuts against the air flowing pipe 51 when the supporting pipe 55 has been plugged into the air flowing pipe 51.

In some embodiments, the supporting pipe 55 further includes a guiding end 551. The guiding end 551 is connected to an end of the first pipe 552 opposite to the transmission pipe 553, namely, the guiding end 551 is arranged at the front end of the first pipe 552. The cross section of the guiding end 551 is substantially tapered with the outer diameter of the distal end thereof being less than the diameter of the air flowing pipe 51, thereby enabling the supporting pipe 55 to be aligned with the center through hole 210 of the air flowing pipe 51.

Referring to FIG. 22, the reservoir 60 in some embodiments is substantially cylindrical, and is formed by rolling cotton sheet. Referring to FIG. 3 again, the reservoir 60 wraps the atomizer assembly 50, and tightly resists the wick 52 of the atomizer assembly 50, thereby enabling solution in reservoir 60 is sucked into the air flowing pipe 51 by virtue of the capillarity of the wick 52. The bottom end of the reservoir 60 is inserted into the accommodating portion 4323, and the top end of the reservoir 60 abuts against the rear end of the supporting pipe 55, to prevent the reservoir 60 from blocking the center through hole 210 of the air flowing pipe 51.

The power supply assembly 70 in some embodiments includes a cylindrical lithium battery. The power supply assembly 70 is housed in the housing 10, and a clearance is formed between the power supply assembly 70 and the inner surface of the housing 10, to allow air circulation. The air switch 80 in some embodiments is substantially flat cylinder. Referring to FIGS. 8 and 23, the air switch 80 is mounted to the step 330 of the end cover 30, and has an interference fit with the inner sidewall of the end cover 30. A chamber is formed between the air switch 80 and the bottom of the end cover 30, and communicates with the outside. The light emitting unit 90 in some embodiments is a light emitting diode (LED), and is mounted to a side of the bottom wall 31 opposite to the air switch 80.

The electronic cigarette 1 is assembled by executing following steps:

- A. Providing the mounting base 40 and the atomizer assembly 50; the atomizer assembly 50 sleeves on the first extending portion 431 of the rigid support 43;
- B. The wires 531 coupled to the heating member 53 of the atomizer assembly 50 extend through the receiving hole 436, the extending hole 414 in sequence, and further extends through the stopping block 415 arranged at the bottom of the extending hole 414;
- C. Dispersing glue into the accommodating slot 4122 corresponding to the stopping block 415 where the wires 531 penetrate through, to seal the piercing hole 416;
- D. Providing the reservoir 60; the reservoir 60 tightly wraps the peripheral of the atomizer assembly 50;
- E. Providing the housing 10; the mounting base 40, the atomizer assembly 50 and the reservoir 60 are inserted into a first end of the housing 10 by the tubular tool 2; wherein, the annular flange 4130 of the sidewall of the elastic body 41 of the mounting base 40 tightly abuts against the inner surface of the housing 10, to enhance the sealing effect between the mounting base 40 and the housing 10;

14

F. Providing the mouthpiece 20; and the mouthpiece 20 is plugged to a second end of the housing 10 opposite to the first end;

G. Providing the power supply assembly 70; the power supply assembly 70 is inserted into the housing 10 via the first end of the housing 10;

H. The power supply assembly 70 is electrically connected to the wires 531 of the atomizer assembly 50;

I. Providing the end cover 30 the air switch 80, and the light emitting unit 90; the air switch 80 is received in the end cover 30, and the light emitting unit 90 is mounted to a side of the air switch 80 opposite to the bottom wall 31 of the cover 30;

J. The air switch 80 and the light emitting unit 90 are electrically connected to the power supply assembly 70;

K. The end cover 70 together with the air switch 80 and the light emitting unit 90 are plugged into the first end of the housing 10, and the assembling of the electronic cigarette 1 is finished.

Wherein, before the step A is executed, the mounting base 40 is installed firstly. The installation of the mounting base 40 includes following steps:

S1. Providing the head bear 43 and the elastic body 41;

S2. The second inserting portion 433 of the rigid support 43 is plugged into the first center hole 410 of the elastic body 40 from the top end surface 411 of the elastic body 41;

In step S2, before the second inserting portion 433 is plugged into the first center hole 410, the receiving holes 436 defined in the second inserting portion 433 are aligned with the extending holes 414, for allowing the wires 531 to extend through in sequence. The annular protrusions 4101 on the inner wall of the first center hole 410 of the elastic body 41 tightly abuts against the sidewall of the second inserting portion 433, to enhance the sealing effect between the second inserting portion 433 and the elastic body 41.

S3. The main portion 432 of the elastic body 41 abuts against the top end surface 411 of the elastic body 41;

In step S3, the third segment 4326 of the main portion 432 of the rigid support 43 is inserted into the receiving portion 4110 of the top end surface 411 of the elastic body 41, and the second segment 4325 abuts tightly against the top end surface 411 of the elastic body 41. Furthermore, the limiting portion 4330 adjacent to the distal end of the second extending portion 433 of the rigid support 43 hooks the annular step 4327 of the bottom end surface of the elastic body 41, to lock the elastic body 41 to the rigid support 43.

Hereinafter, combined with the work principle of the electronic cigarette 1 to illustrate the present invention:

When a “sucking” action takes place at the mouthpiece 20, a negative pressure is formed in the inner space of the housing 10, namely, a variation air pressure is formed. When the air switch 80 detects the variation air pressure, the air switch 80 is actuated to conduct the power supply assembly 70 and the heating member 53 of the atomizer assembly 50, and the heating member 53 is heating to atomize the solution sucked in the wick 52 disposed within the air flowing pipe 51 to form smoke. At the same time, the air switch 80 also conducts the light emitting unit 90 and the power supply assembly 70 when the air switch 80 detects the variation air pressure, to simulate firework effect of burning cigarette.

Furthermore, at the time of the negative air pressure is formed, external air (hereinafter, first air) firstly enter into the housing 10 by passing through the inlet 314 of the end cover 30 and the guiding groove 335 in sequence. The first air further flows into the second center hole 434 of the rigid support 43 along the clearance between the power supply

assembly 70 and the inner wall of the housing 10, and then enter into the air flowing pipe 51 of the atomizer assembly 50 via the second center hole 434. Finally, the first air together with the smoke atomized by the atomizer assembly 50 flow out of the housing 10 by passing through the supporting pipe 55 and the mouthpiece 20, to simulate sucking cigarette.

At the time of the negative air pressure is formed, another air (hereinafter, second air) enter into the electronic cigarette 1 by passing through the aperture 313 and the inner guiding groove 336 in sequence. The flowing procedure of the second air is the same to the first air, and not repeat to illustrate the flowing procedure of the second air here.

FIG. 24 illustrates an atomizer assembly 50a in a second embodiment. The atomizer assembly 50a includes the air flowing pipe 51, a wick 52a, the heating member 53, the positioning sleeve 54, and the supporting pipe 55. An end (inlet) of the air flowing pipe 51 sleeves the first inserting portion 431 of the rigid support 43 (see FIGS. 3 and 4), and communicates with the second center hole 434 of the rigid support 43. The wick 52a traverses the sidewall of the air flowing pipe 51 with two opposite ends extending out of the air flowing pipe 51. The ends of the wick 52a extending out of the air flowing pipe 51 are coupled to the reservoir 60, to suck solution in the reservoir 60 into the air flowing pipe 51. One end of the wick 52a extending out of the air flowing pipe 51 extends downward, and the other end of the wick 52a extending out of the air flowing pipe 51 extends upwardly. In relative to the configuration of the wick 52 with both ends thereof extending downward illustrated in FIG. 18, the configuration of the wick 52a enables solution in the top of the reservoir 60 and solution in the bottom of the reservoir 60 to be evenly guided into the air flowing pipe 51. The heating member 53 engages with a portion of the wick 52a disposed within the air flowing pipe 51, and atomizes the solution sucked into the portion of the wick 52a by heating. The positioning sleeve 54 sleeves on the air flowing pipe 51 and is coaxial with the air flowing pipe 51, to reinforce a particular portion of the air flowing pipe 51. The supporting pipe 55 sleeves on the outlet of the air flowing pipe 51 to protect the air flowing pipe 51 from being deformed when pressed, thereby preventing the air flowing pipe 51 from blocking smoke flowing therein. The supporting pipe 55 further prevents the reservoir 60 from being excessively deformed when an external force radially exert on the electronic cigarette 1, thus, leakage of solution from the reservoir 60 is avoided.

FIG. 25 illustrates an atomizer assembly 50b in a second embodiment. The atomizer assembly 50b includes the air flowing pipe 51, two wicks 52b, the heating member 53, the positioning sleeve 54, and the supporting pipe 55. An end (inlet) of the air flowing pipe 51 sleeves the first inserting portion 431 of the rigid support 43 (see FIGS. 3 and 4), and communicates with the second center hole 434 of the rigid support 43. The wicks 52b traverse the sidewall of the air flowing pipe 51 with two opposite ends extending out of the air flowing pipe 51. The ends of each wick 52b extending out of the air flowing pipe 51 are coupled to the reservoir 60, to suck solution in the reservoir 60 into the air flowing pipe 51. Two opposite ends of one wick 52b extending out of the air flowing pipe 51 extends downward, and two opposite ends of the other wick 52b extending out of the air flowing pipe 51 extends upwardly. In relative to the configuration of the wick 52a illustrated in FIG. 24, the configuration of the wick 52b enhances the capability of sucking solution, and also enables solution in the top of the reservoir 60 and solution in the bottom of the reservoir 60 to be evenly guided to the

air flowing pipe 51. The heating member 53 engages with a portion of the wick 52b disposed within the air flowing pipe 51, and atomizes the solution sucked in the portion of the wick 52b by heating. The positioning sleeve 54 sleeves on the air flowing pipe 51 and is coaxial with the air flowing pipe 51, to reinforce a particular portion of the air flowing pipe 51. The supporting pipe 55 sleeves on the outlet of the air flowing pipe 51 to protect the air flowing pipe 51 from being deformed when pressed, thereby preventing the air flowing pipe 51 from blocking smoke flowing therein. The supporting pipe 55 further prevents the reservoir 60 from being excessively deformed when an external force radially exert on the electronic cigarette 1, thus, leakage of solution from the reservoir 60 is avoided. Furthermore, only one of the wicks 52b is arranged with the heating member.

FIG. 26 illustrates an air flowing pipe 51c in some embodiments. For conveniently installing the wick 52, a cut 512c is defined in the sidewall of the air flowing pipe 51c. The cut 512c is arranged above and communicates with the holes 510. The cut 512c allows two portions of the air flowing pipe 51c divided by the cut 512c to be split to angle with each other, whereby the wick 52 can be placed laterally into the holes 510 conveniently via the cut 512c without aligning and extending through the holes 510. The wick 52c in some embodiments includes a first section 5121c and a second section 5123c connected to the first section 5121c. The first section 5121c extends laterally and outwardly. The second section 5123c extends to and communicates with the holes 510.

FIG. 27 illustrates an air flowing pipe 51d in some embodiments. For conveniently installing the wick 52, a cut 512d is defined in the sidewall of the air flowing pipe 51d. The cut 512d is arranged above the holes 510. The cut 512d extends from the top end surface of the air flowing pipe 51d to the holes 510. The cut 512d allows two portions of the air flowing pipe 51d divided by the cut 512d to be split to angle with each other, whereby the wick 52 can be placed laterally into the holes 510 conveniently via the cut 512d without aligning and extending through the holes 510.

FIG. 28 illustrates an air flowing pipe 51e in some embodiments. For conveniently installing the wick 52, a cut 512e is defined in the sidewall of the air flowing pipe 51e. The cut 512e is arranged below the holes 510. The cut 512e extends from the bottom end surface of the air flowing pipe 51e to the holes 510. The cut 512e allows two portions of the air flowing pipe 51e divided by the cut 512e to be split to angle with each other, whereby the wick 52 can be placed laterally into the holes 510 conveniently via the cut 512e without aligning and extending through the holes 510.

Although information as to, and advantages of, the present embodiments have been set forth in the foregoing description, together with details of the structures and functions of the present embodiments, the disclosure is illustrative only; and changes may be made in detail, especially in the matters of shape, size, and arrangement of parts within the principles of the present embodiments to the full extent indicated by the broad general meaning of the terms in which the appended claims are expressed.

What is claimed is:

1. An atomizer assembly, used for an electronic cigarette, the atomizer assembly comprising:
an air flowing pipe;
a wick extending laterally through a sidewall of the air flowing pipe;
and a heating member disposed within the air flowing pipe and engaging with the wick;

wherein the sidewall of the air flowing pipe defines two opposite holes; the wick extends through the holes with two opposite ends thereof extending out of the air flowing pipe; the sidewall of the air flowing pipe further defines a cut; the cut communicates with the holes, thereby enabling the wick being placed into the holes by passing laterally through the cut, the atomizer assembly further comprises a supporting pipe, the supporting pipe is plugged into an outlet of the air flowing pipe, the supporting pipe and the cut are on a same side of the holes;

wherein the supporting pipe comprises a first pipe, a transmission pipe connected to the first pipe, a second pipe connected to an end of the transmission pipe opposite to the first pipe, and a resisting portion connected to the second pipe opposite to the transmission pipe, a cross section of the transmission pipe is tapered, an end of the transmission pipe with bigger diameter is connected to the second pipe, the other end of the transmission pipe is connected to the first pipe, the supporting pipe is tightly secured to the air flowing pipe, an outer diameter of the resisting portion is greater than an outer diameter of the air flowing pipe, and the resisting portion abuts against the air flowing pipe when the supporting pipe has been plugged into the air flowing pipe.

2. The atomizer assembly as described in claim 1, wherein the cut is arranged above the holes.

3. The atomizer assembly as described in claim 1, wherein the cut comprises a first section extending laterally and outwardly and a second section connected to the first section, the second section extends to and communicates with the holes.

4. The atomizer assembly as described in claim 1, wherein the heating member is a wire and coils around a section of the wick disposed within the air flowing pipe.

5. The atomizer assembly as described in claim 1, further comprising a positioning sleeve, wherein the positioning sleeve sleeves on a portion of the air flowing pipe where the cut is defined.

6. The atomizer assembly as described in claim 5, wherein the inner diameter of the positioning sleeve is substantially equal to the outer diameter of the air flowing pipe; the length of the positioning sleeve is greater than the maximum length of the cut extending along the longitude of the air flowing pipe.

7. An electronic cigarette comprising:

a housing;
a mounting base;
a reservoir;
a power supply assembly;
a mouthpiece defining a center through hole;
an end cover; and

an atomizer assembly, wherein the atomizer assembly comprises an air flowing pipe, a wick extending laterally through a sidewall of the air flowing pipe, and a heating member disposed within the air flowing pipe and engaging with the wick; the sidewall of the air flowing pipe defines two opposite holes; the wick extends through the holes with two opposite ends thereof extending out of the air flowing pipe; the sidewall of the air flowing pipe further defines a cut; the cut communicates with the holes, thereby enabling the wick being placed into the holes by passing through the cut, the atomizer assembly further comprises a supporting pipe, the supporting pipe is plugged into an outlet

of the air flowing pipe, the supporting pipe and the cut are on a same side of the holes;

wherein the mouthpiece and the end cover two opposite ends of the housing; the mounting base, the atomizer assembly, the reservoir, and the power supply assembly are housed in the housing; the mounting base is arranged in the middle of the housing; the atomizer assembly is mounted to the mounting base and is arranged between the mouthpiece and the mounting base; the reservoir is disposed at the peripheral of the atomizer assembly; the power supply assembly is arranged between the mounting base and the end cover and is electrically connected to the atomizer assembly; wherein the supporting pipe comprises a first pipe, a transmission pipe connected to the first pipe, a second pipe connected to an end of the transmission pipe opposite to the first pipe, and a resisting portion connected to the second pipe opposite to the transmission pipe, a cross section of the transmission pipe is tapered, an end of the transmission pipe with bigger diameter is connected to the second pipe, the other end of the transmission pipe is connected to the first pipe, the supporting pipe is tightly secured to the air flowing pipe, an outer diameter of the resisting portion is greater than an outer diameter of the air flowing pipe, and the resisting portion abuts against the air flowing pipe when the supporting pipe has been plugged into the air flowing pipe.

8. The atomizer assembly as described in claim 1, wherein the supporting pipe further comprises a guiding end, the guiding end is connected to an end of the first pipe opposite to the transmission pipe, a cross section of the guiding end is tapered, an outer diameter of a distal end of the guiding end is less than a diameter of the air flowing pipe.

9. The electronic cigarette as described in claim 7, wherein the supporting pipe further comprises a guiding end, the guiding end is connected to an end of the first pipe opposite to the transmission pipe, a cross section of the guiding end is tapered, an outer diameter of a distal end of the guiding end is less than a diameter of the air flowing pipe.

10. The electronic cigarette as described in claim 7, wherein the mounting base comprises an elastic body engaging with an inner sidewall of the housing of the electronic cigarette, and a rigid support for supporting the atomizer assembly of the electronic cigarette; the elastic body defines a first central hole, and the rigid support is inserted into the first central hole; wherein the mouthpiece and the end cover respectively cover two opposite ends of the housing; the mounting base, the atomizer assembly, the reservoir, and the power supply assembly are housed in the housing; the mounting base is arranged in the middle of the housing; the atomizer assembly is mounted to the mounting base and is arranged between the mouthpiece and the mounting base; the reservoir is disposed at the peripheral of the atomizer assembly; the power supply assembly is arranged between the mounting base and the end cover and is electrically connected to the atomizer assembly; the elastic body comprises a top end surface, a bottom end surface opposite to the top end surface, and a sidewall surface connecting the top end surface with the bottom end surface, the first central hole extends from the top end surface to the bottom end surface; and wherein the rigid support comprises a first inserting portion, a main portion, a second inserting portion, and a second central hole; the first inserting portion and the second inserting portion are coupled to a top side and a bottom side of the main portion respectively, and are inserted into the

19

atomizer assembly and the elastic body respectively; the second central hole extends through the first inserting portion, the main portion, and the second inserting portion in sequence; the second inserting portion is inserted into the first central hole from the top end surface.

11. The electronic cigarette as described in claim 10, wherein a plurality of annular flanges protrude radially and outwardly from the sidewall of the elastic body, each annular flange extends along the contour of the sidewall, two adjacent annular flanges are spaced apart from each other, the maximum outer diameter of each annular flange protruding from the sidewall of the elastic body is greater than the inner diameter of the housing; and/or the inner surface of the first central hole is provided with at least two annular protrusions, the annular protrusions are spaced apart, the annular protrusions tightly abut against the sidewall of a second embedding portion.

12. The electronic cigarette as described in claim 11, wherein the bottom end surface of the elastic body recesses to define a plurality of guiding slots, the guiding slots surround the first central hole and are arranged radially, each guiding slot extends from the sidewall surface of the elastic body to the first central hole.

20

13. The electronic cigarette as described in claim 12, wherein the bottom end surface recesses to define an annular step surrounding the first central hole, the annular step is coplanar with the bottom of the guiding slots; and a hook-shaped limiting member is arranged adjacent to a distal end of the second inserting portion, the limiting member is arranged along a contour of the second inserting portion, the diameter of the limiting member is greater than the diameter of the first central hole of the elastic body, the limiting portion hooks the annular step of the bottom end surface of the elastic body.

14. The electronic cigarette as described in claim 13, wherein the middle of the sidewall of the second inserting portion recesses to define a groove, the groove extends from the end surface of the second inserting portion to the top end surface of the limiting portion in a direction parallel to the axis of the second inserting portion, and extends laterally and upwardly through the second inserting portion and the limiting portion.
